UNITED STATES PATENT OFFICE.

ALBERT E. GREENE, OF MEDINA, WASHINGTON.

ELECTRODE MECHANISM FOR ELECTRIC FURNACES.

Application filed March 5, 1923. Serial No. 623,036.

My present invention relates to electrode cranes for electric furnaces and more particularly to improvements in the construction of the electrode holders.

5 In my co-pending application for patent, Serial No. 279,776, filed February 28, 1919, I describe and claim certain improvements in electrode holders and electrode cranes and my present application is a continuation in part 10 of my earlier application above mentioned.

I have found that electrode cranes for electric furnaces should be strongly constructed but constructed in such manner that the position of the electrode in horizontal 15 plane can be quickly and easily adjusted as for example when a new roof is placed on the furnace and the electrode hole on the roof does not quite coincide with the position of the hole in the one previously used.

20 It is also important to be able to adjust and maintain the relative angle between the horizontal arm of the electrode holder and the mast or vertical guide-beam of the crane so that when an electrode touches the bottom 25 or the charge in the furnace chamber, it will not cause movement of the arm which will break the electrodes or electrode joints. My present invention has to do with improvements relating to these features.

30 One object of my present invention is an electrode holder which can be easily and quickly adjusted. In my previous application, of which this case is a continuation in part, I described an improvement in the electrode holder arms by which the horizontal 35 distance between the electrode and the vertical guide-beam or mast could be adjusted. My present application describes an improved means of adjustment of the length 40 of the electrode arm as more fully described hereafter.

45 Another object of my present invention is an improved construction of electrode holder arm whereby the horizontal position of the electrode may be readily and easily adjusted and this feature of my present invention has to do with the pivoted joint at the outer end of the electrode holder arm described more fully hereafter.

50 Another feature of my invention relates to the construction of the electrode holder arm and more particularly has to do with the use of channels such as structural steel channels to form the horizontal part of the electrode holder arm and to provide space between them for a spacing member which

can be adjusted lengthwise of the channels.

Another object of my present invention relates to the construction of the trolley member which engages the mast or vertical 60 guide beams of the electrode cranes. This feature relates to the use of upper and lower trolley wheels, the upper wheel or wheels engaging a surface or surfaces of the vertical guide-beam in one plane and the lower 65 trolley wheel engaging a parallel surface but opposed to the first mentioned plane. More particularly this feature has to do with the use of vertical I-beams as the masts for the electrode cranes with an upper 70 roller pressing against the back of the I-beam and a lower roller pressing against the front surface of the I-beam whereby the arm is held in substantially horizontal position. 75

Another object of my invention relates to the adjustment of the angle between the outwardly extending horizontal arm of the electrode holder and the vertical guide-beam or mast along which the electrode holder 80 operates. This feature comprises a supporting bar connected at its outer end to the horizontal arm of the electrode holder and connected at its other end to the trolley member which operates up and down in 85 connection with the mast or vertical guide-beam and this feature provides for adjusting the angle between the horizontal arm and the vertical beam so as to raise or lower the outer end of the horizontal arm of the electrode holder. 90

Another feature of my invention relates to the use of adjusting rollers which engage opposing surfaces with respect to both the upper and lower trolley wheels to adjust 95 the position of the roller axis towards or away from the electrode and so as to prevent the electrode holder arm from changing its angle with the vertical beam as otherwise might happen when the electrode held by the 100 holder touches the solid charge in the furnace and exerts an upward pressure on the outer end of the arm. Without the use of these adjusting rollers there is a tendency to break the joints between electrodes when 105 the electrode is lowered until it touches the charge but with the use of these adjusting rollers I have found that this tendency to break the nipples is largely eliminated.

Another feature of my invention relates 110 to the construction of these adjusting rollers whereby they are mounted on pins but the

- pins are constructed so that the rollers are eccentric of the axis of the pin proper and by turning the pin around, the space or clearance between the roller and the surface of the vertical guide beam may be adjusted. Another feature of my invention relates to the construction of the electrode holder arm whereby rollers which engage the vertical beam are placed at the end of the horizontal arm member and rollers are placed at the end of the sloping member which connects to the electrode holder arm, and the space between the horizontal arm and the sloping arm which extends downwardly from the horizontal arm may be adjusted by means of bolts connecting the roller ends of these two arms or the distance of the roller axis from the electrode may be adjusted.
- Another feature of my invention relates to the construction of the electrode holder clamping member which is attached to the end of the electrode holder arm by means of the insulated joint and which is constructed in a special way to facilitate the insertion of the electrode contacts which may be water cooled.

Another feature of my invention relates to the construction of the electrode contacts providing for water cooling of these contacts and providing also a special means of connecting the conductors which bring the current to the electrode contacts. These and other features of my invention will be more fully described hereafter.

Another feature of my invention relates to the mounting of the clamping member adjustably on the end of a pipe shaped arm and to the insulation between the contact clamping parts and the end of the pipe arm and also means for tightening and loosening the clamping member over the insulation of the pipe arm.

I will now describe these various features of my invention with reference to the annexed drawings.

In the drawings I have shown in Fig. 1 a side elevation view of an electrode crane embodying my present invention and showing an electrode holder with rollers or trolley wheels engaging the surfaces of a vertical I-beam.

Fig. 2 is a plan view of the electrode holder and I-beam shown in Fig. 1, the I-beam in section.

Fig. 3 is a side elevation view of an electrode holder, the outer end of which is like the electrode holder in Fig. 1 and the I-beam end of which is different from the electrode holder in Fig. 1 in having a set of trolley wheels placed above the outwardly extending arm instead of below it.

Fig. 4 is an elevation view of a modified form of electrode holder, partly in section, showing the insulation between the horizon-

tal pipe shaped arm and the electrode clamping member mounted on the pipe arm.

Fig. 5 is a plan view of the electrode holder shown in Fig. 4.

Fig. 6 is a sectional elevation view of one of the electrode contacts of the holder shown in Fig. 4.

Fig. 7 is an elevation view of the hinge clamping portion of the electrode holder shown in Fig. 5.

Fig. 8 is an end elevation view of the clamping member of the electrode holder shown in Fig. 4.

Fig. 8a is a plan view of the eccentric of Fig. 8.

Fig. 9 is an elevation partly in section of the arm end piece of an electrode holder which fits in between the two channels of the arm, and this section shows the insulating bushings and the insulating material between the contact clamp and the U-shaped piece which latter fits over the arm end and is pivoted about a vertical bolt and supports the contact clamp for holding the electrode.

Fig. 10 is a plan view of the parts shown in Fig. 9 and is a section taken along the line A—A in Fig. 9.

Fig. 11 is a modification of my invention showing an electrode trolley with four wheels engaging the outer surfaces of the vertical beam and showing a pipe arm extending outwardly from the I-beam together with an adjusting bolt which serves to fix the angle between the outwardly extending pipe arm and the vertical beam. This adjusting bolt is fitted with a turn-buckle for quick adjustment.

Fig. 12 is an elevation view of the end of an electrode holder arm showing the pipe arm and the clamping member which fits over the pipe arm but which is insulated from it and showing the clamping members mounted thereon.

Fig. 13 is a plan view of the parts of the electrode holder shown in Fig. 12.

Fig. 14 is a diagrammatic view of an electrode holder arm showing the use of a turn-buckle for adjusting the angle between the outwardly extending arm and the vertical beam.

Fig. 15 shows an elevation view of one type of electrode contact of my present invention.

Fig. 16 is another view of the same electrode contact shown in Fig. 15.

Fig. 17 is an elevation view partly in section of an adjusting roller of an electrode holder for engaging the surfaces of a vertical beam.

Fig. 18 is a plan view of the roller shown in Fig. 17.

These and other features of my invention will be more fully described hereafter.

Referring to Figs. 1 and 2, the electrode holder shown in these two figures is de-

signed to operate along a vertical I-beam 1 which is shown in section in Fig. 2. The outwardly extending arm of the electrode holder comprises two channels 2 and 3 with 5 their flanges extending toward each other. The flanges are cut off at the ends of the channels where the channels extend by the vertical I-beam. The end of one of the flanges may be seen at 4 in Fig. 1. The 10 purpose of cutting off this part of the flange is so that the main web of the channel may be in close proximity to the rollers represented by the dotted lines 5 and 6 in Fig. 1 and shown also at 5 and 6 in Fig. 2. At 15 the outer end of the electrode arm channels is an end piece 7 held in place between the two channels by a bolt 8. Against the channels are two sloping members which may be I-beams or angles or bolts as shown at 9, 20 one on each side of the arm. These sloping members 9 are provided with rollers shown in dotted lines in Fig. 1 at 10 and 11. Between the horizontal channel arm and the downwardly extending arm is a bolt 12 with 25 right and left hand threads screwing into the brackets 13 at the lower end and 14 at the upper end. These brackets are attached to the horizontal arm and the sloping arm by means of bolts as indicated in Fig. 1. 30 There is one of these bolts on each side of the I-beam as indicated in Fig. 2. A spacer indicated by dotted lines at 15 in Fig. 1 and at 16 in Fig. 2 serves to separate the channels and also provides a place for connecting 35 the cable 17 for raising or lowering the arm.

The end piece 7 is provided with a slotted hole for the bolt 8 and the position of the end piece 7 between the channels may be fixed as desired and the end piece can be 40 held in place by tightening the nuts on the bolt 8. In this way the position of the electrode may be changed, that is, the distance between the electrode and the I-beam may be increased or diminished by the 45 length of the slotted hole in the end piece 7. The end piece 7 is shown in further detail in Figs. 9 and 10 and will be described more fully in connection with these figures. The 50 end piece 7 is fitted with a U-shaped piece over the bolt 18 as a pivot and by loosening the nut on this bolt 18 the position of the electrode around bolt 18 as a center can be 55 adjusted. The vertical bolt 18 and the horizontal bolt 19 serve to connect the contact clamp 20 to the electrode arm with suitable insulation between to prevent the flow of current.

The contact clamping mechanism comprises the main contact clamp 20 shown in 60 plan in Fig. 2 and the hinge clamp 21 is mounted on the main clamp 20 by means of a pivot bolt or pin 22. The mechanism for opening and closing the jaws of these clamps comprises an eccentric member 23 with a handle 24 and also an eye-bolt 25 which

connects with the hinge clamp 21 with nuts 26 and 27. This mechanism for opening and closing the jaws is fully described in my co-pending application, Serial No. 279,776, filed Feb. 28, 1919, of which case my present 70 application is a continuation.

The electrode 28 is held between two contacts 29 and 30, which in turn are held between the main contact clamp and the hinge clamp already described. The contact 30 is 75 shown in elevation in Fig. 1. A lug 31 is attached to the upper end of the contact and is provided with holes into which cable conductors may be brazed for carrying current from the source of supply to the contact. 80 These contacts may be water cooled and the two holes indicated at 30 in Fig. 1 represent the inlet and outlet holes for carrying the water. The construction of these contacts is more fully described in reference to Figs. 85 15 and 16.

The electrode holder shown in Figs. 1 and 2 is held in place against the vertical I-beam by means of the rollers 6 and 10. These rollers are mounted on suitable pins or bolts 90 and may be provided with special eccentric bearings if desired. The weight of the electrode on the outer end of the arm will press the roller 10 against the flat surface of the beam toward the electrode, and the roller 6 95 will press against the outer surface of the beam which surface is away from the electrode. The other two rollers 5 and 11 are provided for adjustment purposes. These 100 rollers may be mounted eccentrically on the bolts which extend through them as shown in more detail in Fig. 17.

When the electrode holder is lowered until the electrode rests on the charge in an electric furnace, the weight of the part of the electrode holder arm away from the electrode will tend to force the roller 6 away from the back surface of the beam or else to force the front roller 10 away from the front surface of the beam. If this happens, there is 105 a strain on the electrode which tends to break the joints between the electrode sections. To prevent such undesired movement of the rollers and consequent tendency to break nipples, the adjusting rollers 5 and 11 are provided and the pins on which they 110 are mounted may be rotated until the clearances between the rollers 5 and 11 and the I-beam are as small as desired for the easy operation of the holder up and down on the I-beam. Other means may be used for adjusting these rollers, for example, slots may 115 be provided in the side channels or in the downwardly sloping arms and the rollers may be moved toward the I-beam or away from it to the desired extent. When these rollers 5 and 11 are practically in contact with the I-beam surfaces, then there is 120 practically no tendency for the joints of the electrodes to break.

When it is desired to shift the position of the electrode with respect to the I-beam, this may be done by loosening the nut of the bolt 8 which makes it possible to shift the electrode in or out from the I-beam, or by loosening the nut of the bolt 18, the horizontal position of the electrode about 18 as a pivot may be changed. Or by turning the bolt 12 and the corresponding bolt on the opposite side of the I-beam, the angle between the horizontal arm and the I-beam may be changed. These adjustments make it very simple to adjust the position to the path of movement of the electrode as it is raised or lowered on the I-beam.

Fig. 3 shows a modified form of electrode holder comprising a horizontal arm 32 mounted to operate on rollers which are held in place on a suitable side plate 33 so as to engage the surfaces of the vertical beam 34. The lower roller mounted on the arm 32 is shown at 35 and engages one of the back flanges of the I-beam 34. The upper roller 36 engages one of the front flanges of the I-beam 34 so that the weight of the electrode held in the clamp at the end of the arm presses these rollers 35 and 36 against the back and front flanges of the beam respectively. An adjusting roller (not shown) may be provided to engage the front inner surface of the I-beam so as to keep the roller 35 in the desired position and another adjusting roller 38 may be provided to keep the upper roller 36 in the desired position. A support bolt member 39 is provided between the upper part of the side plate and the bolt 40 at the outer end of the arm. This bolt 39 may be adjusted in any well known manner, as for example, by means of a turn-buckle as described hereafter so that by shortening this bolt 39 and therefore shortening the distance between the roller 38 and the bolt 40, the arm 32 may be raised, that is the outer end of it may be raised with respect to the end engaging the I-beam.

With regard to the electrode holder shown in Fig. 3, it will be noted that the outwardly extending arm member 32 of the electrode holder is connected to the side plate 33 by means of two bolts, one of which extends thru the roller 35 and the other of which extends thru the side plate 33 and arm 32 on the electrode side of the I-beam 34. It is possible to support the weight of the electrode holder arm and electrode by this means, independently of the use of the supporting bolt 39 referred to. The adjusting roller on the back side of the I-beam at the lower end of the plate and opposite the roller 35 is not shown. It is mounted in the plate opposite 33 on the other side of the I-beam. All of the rollers are preferably mounted on eccentric pins described elsewhere in this specification,—that is the upper roller

36 and lower roller 35 and the corresponding rollers on the back side of the I-beam which are not shown and also the other adjusting rollers like that at 38 and the rollers at the lower end of the plate which engage the inner I-beam flanges opposite the roller 35, are all preferably eccentrically mounted. Altho the roller 38 engages the outer surface of the I-beam, that is the surface nearest to the electrode, nevertheless adjusting rollers to take the place of roller 38 might be mounted in the side plate 33 and other side plate near the top of these plates in such manner as to engage the inner back flanges of the I-beam which flanges are opposite the inner flanges engaged by roller 36 and its corresponding roller in the other side plate back of the I-beam. The adjustment of the roller 35 and its corresponding roller in the other side plate back of roller 35 are entirely independent of each other. That is, roller 35 is mounted on an eccentric pin and can have its axis moved up or down or in towards the electrode or out away from the electrode, independently of the position of the axis of the roller corresponding to and back of the roller 35. For example, if the axis of the roller 35 be moved farther away from the electrode, this movement of the roller axis will shift the position of the electrode backward from that shown in Fig. 3. Thus by adjustment of the axis of the roller 35 and of the corresponding back lower roller, or either of them independently the position of the end of the electrode arm and therefore the position of the electrode can be moved horizontally in a direction approximately at right angles to the arm axis, that is either back from the position shown in Fig. 3 or in the opposite direction. These rollers mounted on shafts with eccentric axes on opposite sides of the I-beam or vertical guide beam constitute means for the horizontal adjustment of the electrode position. Either this means or the means shown in Figs. 1 and 2 comprising the pivotal movement about the pin 18 may be used, or both of them may be used. The adjustment of the position of the roller pins about their eccentric axes provides, in addition to the above adjustments, means for adjusting the angle of the electrode holder arm 32 with the vertical guide beam, and therefore means for adjusting the angle of the electrode with the vertical. That is, by moving the axis of roller 35 and also the axis of the corresponding roller back of it, nearer to the electrode without changing the position of the axes of the upper roller 36 and its corresponding roller back of it with respect to the trolley, the angle of the arm 32 with the I-beam will be changed. This means for changing the angle of the electrode with the vertical is independent of the means

shown in other figures such as in Fig. 1 and Fig. 11 and either means may be used independently of the other or both may be used. Altho the eccentricity of these roller shaft axes may be small, for example $\frac{1}{16}$ " yet the movement of the arm is effective. The stay bolt 39 may merely serve as a supporting stay bolt without moving the arm. The rollers like 35 in Fig. 3 may be provided with eccentric adjustment similar to that described with regard to Fig. 17 and Fig. 18 and the roller pin may be provided with the same flattened end as shown in Fig. 17 at 175 and also with the tightening nut to hold the pin in adjusted position. Thus, in order to change the position of the roller axis, the nut is unscrewed to loosen the pin, the pin is then turned by means of a wrench on the flattened portion like that at 175 in Fig. 17 and then the nut is tightened to hold the axis of the pin in adjusted position.

In certain types of furnaces it is preferable to have the vertical I-beams as short as possible above the furnace structure and in such cases, it is often possible to save space by using the construction of sloping arm shown in Figs. 1 and 2. In other cases, it may not be desirable to keep the trolley structure as low as possible and then a supporting bolt like that at 39 in Fig. 3 may be used.

The arm end piece shown at 41 in Fig. 3 supports the contact clamping mechanism with insulation between it and the clamping mechanism. In this Fig. 3 the side channel 42 is cut away from the line 42 out to the end of the channel so that the construction of the arm end piece will be illustrated. The pin 43 serves as a pivot for the hinge clamp 44. This part of the clamping mechanism 44 is like the part 21 in Fig. 2 and the nut 45 in Fig. 3 corresponds to the nut 27 in Fig. 2, serving to adjust the opening between the jaws of the clamp. The electrode contact is indicated at 46 in Fig. 3.

Referring now to Fig. 4 I have shown here another type of electrode arm construction using a pipe for the horizontal arm. This pipe is shown at 51 in Fig. 4. Outside the pipe 51 but insulated from it is a clamping member 52. The insulation between the pipe 51 and the clamping member 42 is indicated at 53. This insulation may be mica or any suitable insulation which will not be deteriorated by heat. Fig. 5 shows the plan view of this same electrode holder. A bolt 54 serves to tighten the clamp 52 over the pipe 51 and outside the insulation 53. By loosening the nut on this bolt 54, the clamp 52 may be moved along the pipe arm 51 so as to adjust the position of the electrode. The clamping member 52 is provided with two flanges indicated at 55 and 56 which serve to carry the hinge clamp shown at 57 in Fig. 5 and a pivot bolt 58

is provided to permit the hinge clamp 57 to open or close about the pin 58 as a pivot. In Fig. 4 only a portion of the hinge clamp is shown, namely that to the left of the section portions 59 and 60, corresponding to 70 the broken line 61 in Fig. 5.

In Fig. 4 the inside view of the electrode contact may be seen at 62 and the lug at the top of the contact is indicated at 63.

In Fig. 6, I have shown a section of this electrode contact. The surface 62 in Fig. 6 presses against the outside surface of the electrode 64. The lug at the top is shown at 63 and the hole through this lug for a cable is shown at 65. In Fig. 5 the lugs are indicated at 63 for both contacts.

In the plan view in Fig. 5 I have shown the lever handle for the eccentric mechanism for opening and closing the jaws at 66. I have shown this lever bent so that 85 when the clamp is closed this lever may be in close proximity to the hinge clamp 67. By this construction the movement which tightens the clamps or jaws and so presses the contacts against the electrodes is a movement against the trolley which is at the opposite end of the electrode holder arm. And when it is desired to open the jaw the movement is such as to pull the lever 66 away from the vertical beam along which 95 the electrode holder operates. By this construction there is little or no tendency to push the electrodes from one side to the other when opening or closing the jaws. In this Fig. 5, the eye-bolt is shown at 68 and 100 the two adjusting nuts on this bolt are shown at 69 which is inside of the hinge clamp and 70 which is outside the hinge clamp. The threads on the bolt 68 are loose so that the nuts operate easily when a different size electrode is to be used. These nuts may be moved to fit the jaws to the different dimensions required.

Fig. 7 shows the outside of the hinge clamp of the electrode holder in Fig. 5, and 110 59 and 61 are the flanges through which the pivot bolt 58 passes. The hole 71 at the outer end of the hinge clamp is the hole through which the eye-bolt 68 passes.

Fig. 8 is an end view of the outer ends of 115 the jaws of the electrode holder of Figs. 4 and 5 and shows the location of the eccentric lever in section at 72 where it joins the main eccentric boss. The eye-bolt is shown at 73 outside of the eccentric part of the boss. 120 74 is the lower part of the main contact clamp and 75 is the upper part of it and through these two parts 74 and 75, the pin 76 extends. This pin extends through the hole 76 in Fig. 5. The parts 67, 68, 69, and 125 70 are the same parts as indicated by these same numerals in Fig. 5.

Fig. 9 shows the details of the construction used for the end piece of the holder arm and the insulation between it and the electrode 130

clamp. The parts shown in this figure are the end piece 91 shown partly in section, the U piece 92 also shown partly in section, the vertical insulation 93 and the horizontal 5 insulation at the top of the U piece 94, and the section of the main contact clamp shown at 107. The bolts and insulated washers and bushings are also shown as referred to hereafter.

10 The arm end piece 91 is the type of end piece used in the electrode holder shown in Fig. 1. It may be a steel casting and is provided with a slot 96 through which a bolt extends which serves to clamp the channels 15 of the arm end piece, 91. As already stated, by loosening the nut of the bolt shown in Fig. 1 the end piece may be moved lengthwise of the electrode holder channel arms to the distance permitted by the length of the 20 slot 96 and thus the position of the electrode may be changed when desired. After changing the relative position of the end piece inside the channels the connecting bolt is again tightened so that the parts are held 25 in permanent relation to each other. The U piece 92 fits over the top and bottom of the arm end and has a hole in it corresponding to the hole 97 in Fig. 10.

Fig. 10 is a plan view in section along the 30 line A—A of Fig. 9. It will be seen therefore that the U-piece 92 may be moved around the bolt 98 as a pivot. The bolt 98 is insulated from the parts 91 and 92 by means of the insulating bushing 99 which 35 may be a mica bushing. This bushing extends through the bottom flange of the U-piece 92 and extends also through the insulating washer 100 at the bottom in Fig. 9; and this insulating bushing 99 at its upper 40 end extends through the flange 95 of the contact clamp and also through the insulating washer 101. Ordinary cut washers are provided outside the insulating washers. These 45 cut washers are shown at 102 and 103. Inside the insulating bushing 99 is a bolt 98 and the nut 104 on this bolt at the lower end serves to hold all of these parts together.

Another insulated bolt 105 shown in Fig. 50 10 serves to bolt the vertical plates or flanges of the U-piece and of the main contact clamp together, these flanges being shown at 106 and 107 with the insulating plate 93 between them. This bolt 105 is also insulated from both the flanges 106 and 107 by 55 means of an insulating bushing 108 and insulated washers 109 and 110. The insulation used at 93 and 94 and also for the washers like that at 101 may be transite asbestos wood or mica or other suitable insulating 60 material which will not deteriorate when subjected to heat. In Fig. 9 and also in Fig. 10 the pin for the hinge clamp may be seen at 111. The outer end of the main contact clamp is cut off as shown at 112 and the outer end of the hinge clamp is cut off in

the drawing at the sections 113 and 114 in Fig. 9.

The advantage of this construction of electrode holder is that two bolts serve to hold the main contact to the arm end and U- 70 piece but insulate these parts from each other in a very efficient and substantial manner. It will be seen that the pressure comes on the end insulating members 93 and 94 rather than on the bushings 99 and 108 so 75 that there is practically no tendency for this insulation to wear and break down. The width of the insulating piece 94 is the same as the width of the insulating piece 93 shown in plan in Fig. 10, that is, the insulating 80 plate 94 extends clear across the top of the U-piece 92.

In Fig. 11 I have shown a modified construction of trolley with a part of the electrode holder arm extending outwardly therefrom. In Fig. 11 the rollers are mounted on pins at 121, 122, 123 and 124. The downward pressure of the electrode at the outer end of the arm tends to press the rollers on pins 122 and 124 against the back and front 90 faces of the vertical beam 125. The pipe arm 126 may be mounted on pin 123 so that it is adjustable about this pin 123, that is, the angle between the axis of the pipe arm 126 and the vertical beam 125 may be 95 changed or held in any desired position, within the limits desired. I have shown a turn-buckle 127 connected with a bolt 128 which is mounted toward the lower part of the plate 129, on a pin 130 and I have also shown a bolt 131 mounted on the pin 132 through the pipe arm. By turning the turn-buckle which operates on the right and left-hand threads of the bolts 128 and 131, the 100 distance between the pins 130 and 132 may 105 be changed and consequently the arm 126 may be held in any desired position in its angle with the vertical.

In Fig. 12, I have shown a further modification of the clamping member which is 110 mounted at the end of a pipe arm for holding an electrode clamp. The outer end of the pipe arm is shown in Figs. 12 and 13 at 141. The clamp is shown at 142. The bolts 143 and 143^a in these figures serve to 115 tighten this clamp about the pipe and insulation indicated at 144 insulates the pipe from the clamp. The upper clamp 142 is provided with a flange 145 and the lower clamp 142^a is provided with a flange 146 for taking 120 a pin 147. Mounted on this pin 147 are two clamps 148 and 149. These clamps may be provided at the outer ends with an eccentric clamping mechanism as shown in Fig. 5. The outer ends of the clamps in Figs. 12 125 and 13 are not shown. In Fig. 13 the electrode arm is shown in plan at 149 and the contacts may be seen in section at 150 and 151. It will be seen that the position of the electrode may be changed horizontally 130

around the pin 147 as a center the line 147* pointing to the path of the center of the electrode. Likewise the position of the electrode may be changed in the direction of the 5 axis of the pipe arm 141 by sliding the clamp 142 along that arm. The angle of the electrode with the vertical may be changed if desired as indicated in Fig. 14.

Fig. 14 shows a vertical I-beam 152 with 10 a horizontal pipe arm 153 connected vertically by means of suitable rollers on the pins 154 and 155. A downwardly extending arm 156 may be mounted on each side of the horizontal arm 153, using the pin 157, extending through the horizontal arm and also 15 having a roller at its lower end on the pin 158. An adjusting roller 159 may also be provided on this sloping arm. Then between the pins 154 and 158 I may provide 20 two eye-bolts connected together by means of a turn-buckle 160 which serves to adjust the angle between the horizontal arm 153 and the vertical beam 152.

Figs. 15 and 16 show two views of an 25 electrode contact. The surface 161 makes contact with the outside surface of the electrode. In Fig. 16, I have shown a water cooled cavity 162 with openings 163 and 164 for the inlet and outflow of water. 30 These openings may be tapped for standard pipe fittings. The lug 165 which extends upwardly from the main part of the contact has one or more holes in it 166 and into these holes a cable may be brazed as indicated 35 in Fig. 15, which is partly in section. The section here shown illustrates the cable 168 extending into the hole and the portion 169 represents the brazing or welding of the cable to the main part of the lug. To 40 make the joint the cable is inserted in the hole to a distance not quite through it and then the brazing material or the copper is filled in making a solid joint between the cable and the copper of the lug. I prefer 45 to make the contacts of copper but I am not limited to the use of this material and may use iron or aluminum or other metals for this purpose. The advantage of this 50 construction of connecting cables and lugs is that the heat from the furnace does not affect these joints and there is no tendency to loosen.

Figs. 17 and 18 show the construction 55 and operation of the adjusting roller using an eccentric bolt. In Fig. 17 the vertical section of the roller which engages the flat surface of the beam is shown at 171. This roller operates on the surface of the pin shown at 172. The ends of the pin are 60 turned down on the center 173 which is eccentric of the center 174, the latter being the center of the inside of the roller. At the outer end of the pin, the pin is flattened so that it may be turned by means of a

wrench on the surface 175 and the corresponding parallel surface on the opposite side 176. In this way, the pin may be turned about the center 173. It will be seen that turning the pin about the center 173 will serve to move the roller as a whole 70 about this center and to or from the line 176 representing the surface against which the roller operates, and by turning the pin around the center 173, the roller may be moved toward or from the surface represented by the line 176 so as to lessen or increase the clearance between the adjusting roller and that surface. This clearance may be adjusted as desired. The nut 176* in Fig. 18 shows the nut for tightening the 80 roller pin in adjusted position. This nut tightens the pin and holds it against the trolley side 175*. A corresponding nut is provided on the other end of this type of roller. For the type of roller shown in Fig. 85 3 at 35, the roller pin may be provided with a flanged portion to keep the roller on the pin taking the place of the opposite electrode holder side 172* shown in Fig. 18.

In further reference to Figs. 12 and 13, 90 the clamping member 142 may be constructed just like the clamping member 142*, the former fitting over the top of the insulating tube 144 and the other member 142* fitting underneath the insulation and the two 95 clamping members may be held together by bolts 143 and 143*. These bolts extend through the lugs shown in the plan view in Fig. 13, one bolt at each side of the pipe arm 141. These clamping members 142 and 142* 100 may be of cast steel. Each of them has a lug like that shown at 145 in Fig. 13 through which the bolt hole 147 extends. The bolt 147 in Fig. 12 serves as a pivot for the two clamping jaws 148 and 149. These two 105 jaws are shown more clearly in the plan view in Fig. 13. The bolt 147 is provided with a nut 147* on its lower end. By tightening the nut 147*, it is apparent that the members 149 and 148 which are the clamping jaws of the electrode holder, may be held in place against the flange 145 so that 110 there will be no tendency for the jaws to move about the bolt 147 as a center.

It is pointed out, however, that the nut 115 147* does not need to be tightly screwed up on the bolt so as to hold the clamping jaws in fixed position, but on the contrary, this nut 147* may be merely screwed up loosely 120 on the bolt and permit the jaws which hold the electrode to have a certain movement about the bolt 147 as a center. In this way, it is possible to give the electrode holder a certain flexibility so that if the joint between two electrodes is such that it might catch on the roof brick as the electrode is lowered, this flexibility will permit sufficient movement of the electrode holder so that the un-

eveness of the electrode will not interfere with its movement up or down through the roof brick.

It is also pointed out that the insulating tube or bushing 144 may be provided with an extension indicated by the dotted lines at 144^a so that there will be no chance for the jaws or any of the metal parts which are in contact with the electrodes to become short circuited to the electrode arm 141 as might happen when the clamping mechanism is moved to the left in adjusting the horizontal position of the electrode lengthwise of the arm. It is pointed out that this construction of electrode holder shown in Figs. 12 and 13 has a number of advantages in that the clamping members may be cast from the same pattern, one of them being used for the top clamping piece and the other for the bottom clamping piece; also these clamping members can be easily moved lengthwise of the arm and can then be held in fixed position by tightening the clamping bolts like 143; and then in addition, the horizontal position of the electrode may be moved about the bolt 147 as a center, the center of the electrode following the dotted line pointed to by the radius line 147^a. The horizontal position of the electrode may be changed and held in fixed position by tightening the nut on the pivot bolt or this nut may be left loose for flexibility of the electrode clamping members. This electrode holder is extremely simple and yet embodies many points of advantage.

In further reference to the eccentric mechanism for closing the electrode clamping jaws shown in Fig. 8, I have shown a plan view of the eccentric member proper in Fig. 8^a to illustrate the location of the bolt hole and the surface of the eccentric boss which is eccentric of the center of the bolt hole. In Fig. 8^a, the center of the bolt hole is on the center line 72^c and the center of the eccentric boss which engages the eye-bolt is in the center line 72^b. The circumference of the eccentric boss is indicated at 72^a in both Fig. 8^a and in Fig. 8. The eccentric lever is indicated at 72 in both figures. It will be noted that with the lever handle 72 in the closed position as shown in Fig. 8^a, the eye-bolt boss 72^c is in the farthest position to the right, corresponding to the position of the jaws when they are closed as tightly as possible.

It will be understood that the various features of my invention may be combined in different ways and that I do not limit myself to any specific combination of these improvements.

In Fig. 15 I have shown a novel construction of combination electrode contact and lug and cable for carrying current to the electrode. These cables may be mounted on the arm and serve to bring the current

directly to the electrode without any bolted joints in the conductor. The same improvement is also shown in Fig. 6 without water cooling however. The great advantage of this means of conducting current to the electrode is that the bolted joints common to other constructions are done away with and there is no chance for the welded or brazed joint to loosen or for solder to melt and run out and weaken the joint. Thus this combination of electrode contact with integral cable lug having a hole for the cable constitutes a special feature of my invention and in combination with this the use of flexible cables which are brazed directly into this cable lug and yet lead to the power supply while at the same time providing flexibility as is required by movement of the electrode holder, this combination is a further advantageous improvement. The flexible cables are shown at 168 in Fig. 15.

I have shown a number of modifications of my invention. For example I have shown electrode holders with arms mounted near the bottom of the trolley member as in Fig. 3 and other modifications in which the arm is mounted near the top of the trolley member, as in Fig. 1, but it is understood that I do not limit myself broadly to locating the arm in any given position, altho in specific modifications of the invention I may do so. But I may mount the arm any where between the top and bottom parts of the trolley member or side plates without getting away from the novel features of my invention; and I may mount the outwardly extending arm in any suitable way and either by means of bolts as shown and described with regard to Fig. 3,—that is without use of the stay bolt 39, or I may mount the outwardly extending arm on a pivot and adjust its angle with the vertical by means of a turn-buckle bolt. I do not limit myself to the use of I-beams as the vertical guide beam member for the trolley but may use any kind of vertical guide beam, and I mount the rollers to operate on inside flanges of channel shaped members such as the I-beams of Figs. 2 and 3, or the vertical guide beam may be of any general construction as indicated at 125 in Fig. 11 with rollers operating on its outer surfaces. And also I may use either the eccentric means of adjustment of the electrode holder alone or I may combine the other means of adjustment shown with the eccentric means, or I may use other means of adjustment, as for example the slotted means for adjusting the roller axes.

My present invention provides means for adjusting the angle of the electrode with the vertical, and the position of the electrode horizontally in any direction, and does these adjustments in a simple and greatly improved manner.

What I claim is:

1. An electrode crane comprising a vertical guide member having front and back flat opposed surfaces, an electrode holder for holding an electrode and comprising a horizontal arm connected at one end with rollers, one of which engages one of said surfaces of the guide member and another of which engages an opposing surface at a different elevation, a supporting member connected at its outer end with the horizontal arm of the holder and at its lower end to the lower wheel or wheels of said trolley and means for adjusting the distance between the upper and lower wheels.

2. An electrode holder for carrying an electrode comprising upper and lower rollers for engaging opposing surfaces of a vertical guide member, structural members extending horizontally out from the upper rollers for holding the electrode mounted at the outer end, in an electrode clamping device and structural members connecting the lower rollers to the outer end of the horizontal arm and means of adjusting the distance between the upper and lower rollers and holding said rollers in adjusted position.

3. In combination, an electrode crane comprising a vertical member and a trolley member slideable along said vertical member, the trolley having an outwardly extending arm, and one or more rollers engaging a surface of the vertical member and another roller engaging an opposing surface of the vertical member above the first mentioned roller, means of holding the upper and lower rollers a predetermined distance apart and means for adjusting the distance between the upper rollers and a point on the horizontal arm out from the vertical beam and holding the members in adjusted position.

4. In combination, an electrode crane comprising a vertical beam and a trolley engaging the surfaces of the vertical beam and having upper and lower rollers, an arm extending outwardly from said trolley for supporting an electrode, adjustable means of connecting the outer end of the arm with a point on the trolley at a different elevation relative to the outwardly extending arm and means for holding the parts of the electrode holder in adjusted position.

5. An electrode holder for holding an electrode, comprising upper and lower rollers for engaging opposing surfaces of a vertical guide member along which said rollers may operate, and comprising two structural channel shaped members forming the horizontal arm of the holder, an arm end member for holding said structural channels apart at the outer end, means of holding the upper and lower rollers in adjusted position vertically, and one or more structural members extending at an angle from a position on the arm out from the guide beam to

the lower rollers of the holder, whereby the relative position of the horizontal arm may be adjusted.

6. In an electrode holder having two horizontally extending arms comprising structural channels with one or more rollers mounted at one end for engaging a vertical guide mast, and a spacer placed between said structural channels at the outer end to hold them apart and a bolt through the channels and through the end spacing member to hold them together in adjusted position, and means of holding the horizontal arm in approximately horizontal position outwardly from the vertical mast.

7. In an electrode holder for supporting an electrode at its outer end, the means of adjusting the distance between the electrode and the other end of the electrode arm, said means comprising a spacing member held between two horizontally supported structural members, an elongated horizontal hole through two sides of the spacing member and a bolt for holding the spacing member and structural members together whereby the relative position in or out of the spacing member may be adjusted by loosening said bolt.

8. An electrode holder comprising a horizontal arm for holding an electrode at its outer end, said arm comprising two structural channels with their flanges opening toward each other, an arm end member between said channels at the outer end thereof adapted to support the electrode in a suitable clamp insulated from said arm end member and means for adjusting the position of the arm end member lengthwise of the channels and of holding said arm end member in an adjusted position by means of one or more bolts.

9. An electrode holder comprising in combination an outwardly extending arm and arm end member at the outer end of said arm, a bracket pivoted to said arm end around a vertical pin through said bracket and arm end and means for holding an electrode on said bracket and insulated therefrom.

10. In combination, an electrode holder comprising an outwardly extending arm, a bracket at the outer end of said arm pivoted to said arm around a vertical pin, a clamping member bolted to said bracket but insulated therefrom and means of adjusting the position of an electrode held in said holder around said vertical pivot.

11. An electrode holder comprising a horizontal pipe arm, an insulating bushing mounted thereon, a clamping member around said bushing, means for tightening the clamp around the insulated bushing at the desired location lengthwise of the pipe arm, a vertical pin extending through upper and lower flanges on said clamping member

and two jaws for holding an electrode between them, these jaws likewise being mounted on the said vertical pin.

12. An electrode holder comprising a horizontal arm, a clamping device mounted on said arm but insulated therefrom, means of clamping this device in the desired position lengthwise of said arm, an upper and lower extension on said clamping member, each of these extensions having a hole for a vertical pin and two electrode clamping jaws mounted adjustably on said vertical pin.

13. An electrode holder comprising a horizontal arm, an upper clamp and a lower clamp fitting over the end of said arm but insulated therefrom by suitable insulating material, a bolt on each side of said clamps for bolting them together about the end of said arm, an extension each of said clamps for taking a vertical pin beyond the end of said arm and approximately in line with the axis of said arm, said vertical pin carrying two adjustable jaws for holding an electrode between them.

14. An electrode holder comprising an upper and a lower clamp, means for bolting these together about the end of a suitable arm, a vertical pin extending through said clamps and adapted to carry two adjustable jaws mounted on said pin as a center, and means for clamping an electrode between said jaws.

15. An electrode holder comprising a horizontal outwardly extending arm mounted to operate on a vertical beam and to carry an electrode holding mechanism at its outer end, a sloping arm mounted at its outer end on a pin through said horizontal arm and having rollers at its other end to engage said vertical beam, and means for adjusting the angular opening between the horizontal arm and the sloping arm, said means comprising a turnbuckle mounted between said arms.

16. In an electrode holder comprising a vertical beam and a trolley member engaging the surfaces of said beam by means of rollers, an adjusting roller mounted eccentrically on a pin whereby the clearance between the roller and a surface of the vertical beam may be adjusted by turning the pin about its axis.

17. An electrode holder comprising a vertical beam having front and back flat surfaces, a trolley member having rollers, one of which engages one surface and another of which at a different elevation engages an opposing surface when the trolley member is raised or lowered along said vertical beam, two adjusting rollers, one for each of the above mentioned rollers, the adjusting rollers serving to hold the main rollers against the said surfaces of the beam within the desired limits of clearance.

18. An electrode holder comprising a vertical beam, a horizontally extending arm, a

trolley comprising two side plate members, two upper rollers, one engaging a back surface and the other engaging an opposing surface of the vertical beam, and two lower rollers, one engaging a front surface and the other engaging an opposing surface of said beam and means of adjusting the clearance between one upper roller and one lower roller and corresponding surfaces of the beam.

19. An electrode mechanism comprising a clamping member mounted at the outer end of an arm, insulation between said clamping member and said arm, a vertical pivot mounted on said clamping member beyond the end of said arm for carrying an electrode clamping device and means for insulating the outer parts of the clamping device from the main electrode holder arm.

20. In combination in an electrode holder an outwardly extending electrode holder arm and an adjustable arm end member, means for bolting said arm end member in fixed position lengthwise of the axis of said arm, a vertical bolt through said arm end and means for holding an electrode clamping member on said vertical bolt.

21. An electrode holder for an electric furnace, said holder comprising a trolley member mounted on rollers to operate on a vertical beam or mast, and eccentric means for adjusting said rollers with respect to the trolley member.

22. An electric furnace electrode holder having rollers for engaging a vertical guide beam, pins for said rollers to rotate on, means for mounting said pins eccentrically of the roller axis whereby the roller may be moved about the eccentric axis of the pin and means for holding the pin in adjusted position.

23. An electric furnace electrode holder comprising a trolley member for operating vertically along a vertical guide beam, a roller mounted on said trolley member for engaging the surface of said guide beam, a shaft for said roller to rotate on, and means for mounting said shaft on an axis eccentric of the roller axis and for holding said shaft in adjusted position with respect to said eccentric axis.

24. An electric furnace electrode holder as in claim 23 comprising upper and lower rollers engaging a vertical guide beam and mounted eccentrically as in claim 23.

25. An electric furnace electrode holder as in claim 23 with eccentric means for adjusting the rollers and having rollers on opposite sides of the guide beam.

26. An electric furnace electrode holder as in claim 23 in which the roller shaft has a stud extension on the end of the roller shaft for mounting the roller eccentrically of the roller axis and a nut on said stud for holding the shaft in fixed eccentric position about the stud axis.

27. An electric furnace electrode holder as in claim 23 in which the shaft has a threaded extension or stud eccentric the axis of the shaft and a flattened end on said stud so that it may be turned to move the roller shaft about the stud axis. 45
28. An electric furnace electrode holder as in claim 23 in which the trolley member comprises a plate or side member on both sides of the vertical guide beam, said roller shaft having threaded stud extensions integral with the shaft, one on each end thereof and both mounted on the same axis which axis is eccentric of the roller shaft axis. 50
29. An electric furnace electrode holder as in claim 23 in which the roller shaft is mounted on a stud extension on one end of said shaft. 55
30. An electric furnace electrode holder as in claim 23 in which the rollers are adapted to engage the inner surfaces of the flanges of a channel shaped guide beam. 60
31. An electric furnace electrode holder having a trolley member, upper and lower rollers mounted thereon for engaging a vertical guide beam and rolling thereon, said rollers having shafts to rotate on, and means for mounting said shafts in the trolley member eccentrically of the shaft axes and for holding the shafts in adjusted position about said eccentric axes, an arm attached to said trolley member extending outwardly therefrom for holding an electrode, the position of which electrode may be moved by means of said roller shaft adjustments. 65
32. An electric furnace electrode holder comprising a trolley member having rollers engaging the surface of a vertical guide beam, eccentric means for adjusting the position of the roller axis of said rollers, the rollers being so located on the trolley member with respect to the vertical guide beam as to permit adjustment of the angle of the electrode with the guide beam. 70
33. An electrode holder for an electric furnace as in claim 32 except that the eccentric means constitutes means for adjustment of the horizontal position of the electrode with respect to a normal axis of the arm. 75
34. An electrode holder as in claim 32 in which the vertical guide beam comprises a channel shaped member in which a roller operates. 80
35. An electric furnace electrode holder comprising a trolley member for movement along a vertical guide beam, and means for adjusting the axis of the electrode held by said electrode holder with the vertical. 85
36. An electrode holder for an electric furnace, said holder comprising in combination a vertically movable member operating on rollers along a vertical guide member, and means for adjusting the position of the roller axes in the direction of the longitudinal axis of the electrode holder arm held in connection with said vertically movable member. 90
37. An electrode holder for an electric furnace said holder comprising a trolley member carrying an arm for supporting an electrode, rollers mounted on said trolley member to engage a vertical guide member, and slots for the shafts of said rollers whereby adjustment of the roller axis may be made with respect to the trolley member. 95

In witness whereof, I hereunto subscribe my name this 24th day of February, A. D. 1923.

ALBERT E. GREENE
